Primary Examiner — Kevin Rudzinski*Assistant Examiner* — John Reickel(74) *Attorney, Agent, or Firm* — Lewis Roca Rothgerber Christie LLP(57) **CLAIM**

The ornamental design for a display screen with graphical user interface, as shown and described.

DESCRIPTION

The sole FIGURE is a front view of a display screen with graphical user interface showing our new design.

The broken line showing of lettering and numbering is for the purpose of illustrating portions of the article and forms no part of the claim.

1 Claim, 1 Drawing Sheet

See application file for complete search history.
